UNITED STATES PATENT OFFICE.

ERROLD G. BAHL, OF LINCOLN, NEBRASKA.

ELEVATOR CONTROL.

Application filed July 15, 1922. Serial No. 575,157.

To all whom it may concern:

Be it known that I, ERROLD G. BAHL, a citizen of the United States, residing at Lincoln, in the county of Lancaster and State 5 of Nebraska, have invented new and useful Improvements in Elevator Controls, of which the following is a specification.

This invention relates to aeroplane controls, particularly to the elevator, and has 10 for its object the provision of an elevator and control mechanism in which a one piece elevator is employed mounted within a cut away portion at the rear end of the fuselage, the control wires for the elevator 15 being enclosed entirely within the fuselage whereby to lessen wind resistance and to decrease liability of injury to the control.

An important and more specific object is the provision of an elevator which is provided with a single pair of operating horns 20 extending from the upper and lower surfaces thereof, the horns being laterally offset in opposite directions so that the control wires connected therewith will clear the 25 standard of the rudder which is journaled through the fuselage.

An additional object is the provision of an elevator and control therefor, which will be simple and inexpensive in manufacture 30 and installation, highly efficient in use, durable in service, and a general improvement in the art.

With the above and other objects and advantages in view, the invention consists in 35 the details of construction to be herein-after more fully described and claimed and illustrated in the accompanying drawings in which—

Figure 1 is a side elevation of the rear 40 end of the aeroplane showing my device in position, a part of the fuselage being broken away and in section.

Figure 2 is a horizontal sectional view 45 through the fuselage taken immediately above the elevator structure, and

Figure 3 is a fragmentary front elevation of the elevator.

Referring more particularly to the drawings, the letter A designates a portion of 50 the fuselage of an aeroplane, B designates the bearing shoe below the rear end thereof, C designates the vertically disposed rudder post which carries the rudder D and in advance of which is mounted the usual fin E. The details of the rudder structure and means for operating the same are not shown

as forming no part of the present invention.

In carrying out my invention I form the rear end of the fuselage A with a V-shaped 60 cut-out portion 10 and within this cut-out portion is secured a transverse rod or shaft 11 upon which is hinged, as shown at 12, the elevator 13 which is formed in one piece and which is freely movable within the limits defined by the edges of the cut-out portion 10. Extending from the sides of the fuselage are the horizontal fins 14 which are located in advance of the elevator. 70

Suitably secured to and extending above the upper surface of the elevator is a horn 15 which has its end portion apertured, as shown at 16, for connection with a control wire 17 or the like, and secured to and extending from the lower side of the elevator is a similar horn 18, apertured, as shown at 19, for connection with a control wire 20 or the like. The means for applying a pull to either wire 17 or 20 for the purpose of 80 moving the elevator is not shown, as such forms no part of the present invention, it being moreover conventional to provide any suitable lever mechanism for moving these control wires. Owing to the fact that the 85 horns 15 and 18 are located in alignment with and to the rear of the rudder post C, I off-set the extremities of the horns in opposite directions, as shown at 21 and 22, respectively, whereby the operating wires 90 will clear the rudder post, one extending along one side thereof, and the other extending along the other side.

In the operation it will be seen that when the wire 17 or 20 is pulled by any suitable means, not shown, the elevator will be moved from the horizontal position to an upwardly or downwardly inclined position as the case may be, depending upon whether it is desired to ascend or descend. Owing 100 to the offsetting of the horns it will be apparent that the control wires will never interfere with the rudder and that there will consequently be no binding whatever between any of the parts during movement thereof. It is also to be noted that the control wires are located entirely within the confines of the fuselage and that air resistance will consequently be diminished and that danger of injury to the control wires 110 will be reduced to the minimum. Owing to the cutting away of the rear end of the 105

fuselage and the specific arrangement of the parts, it will be apparent that the elevator may conveniently be formed in one piece instead of in two, as is the usual practice.

5 While I have shown and described the preferred embodiment of my invention, it is of course to be understood that I reserve the right to make such changes in the form, construction and arrangement of parts as 10 will not depart from the spirit of the invention or the scope of the subjoined claims.

Having thus described my invention, I claim:—

15 1. In an aeroplane including a fuselage, a vertically disposed rudder post journaled through the rear end of the fuselage and carrying a rudder, an elevator, the rear end of the fuselage being cut away for the reception of the forward edge of the elevator, 20 a transverse rod secured within the innermost portion of the cutout portion, the forward edge of the elevator being hingedly connected with said rod, horns extending upwardly and downwardly from the upper and lower surfaces of the elevator, respectively, and control members secured to the 25 extremities of said horns.

2. In an aeroplane including a fuselage, a vertically disposed rudder post journaled through the rear end of the fuselage and carrying a rudder, an elevator, the rear end of the fuselage being cut-away for the reception of the forward edge of the elevator, 30 a transverse rod secured within the innermost portion of the cut-out portion, the forward edge of the elevator being hingedly connected with said rod, horns extending upwardly and downwardly from the upper and lower surfaces of the elevator, respectively, and control members secured to the 35 40

extremities of said horns, said horns being in alignment with and to the rear of the rudder post and having their extremities offset whereby the control means will be disposed out of contact with the rudder post. 45

3. In an aeroplane including a fuselage, a vertically disposed rudder post journaled through the rear end of the fuselage and carrying a rudder, an elevator, the rear end of the fuselage being cut away for the reception of the forward edge of the elevator, a transverse rod secured within the innermost portion of the cut-out portion, the forward edge of the elevator being hingedly connected with said rod, horns extending upwardly and downwardly from the upper and lower surfaces of the elevator, respectively, and control members secured to the extremities of said horns, said horns being in alignment with and to the rear of the rudder post and having their extremities offset whereby the control means will be disposed out of contact with the rudder post, one horn being offset in one direction and the other in the opposite direction. 50 55 60 65

4. In an aeroplane including a fuselage, and a rudder post journaled through the rear end thereof and carrying a rudder, a transverse shaft secured at the rear end of the fuselage to the rear of the rudder post, an elevator formed in one piece pivoted upon said shaft, horns extending from the upper and lower surfaces of the elevator out of alignment with the rudder post, and control wires connected with the extremities of said horns and contained entirely within the fuselage. 70 75

In testimony whereof I hereto affix my signature.

ERROLD G. BAHL.
